INFLATABLE UMBRELLA

William A. Turner, 205 Sycamore Road,
Franklin, Va. 23851

Filed Sept. 21, 1971, Ser. No. 182,578

Term of patent 14 years

Int. Cl. D3—03
U.S. Cl. D88—3 R

FIG. 1 is a top plan view of an inflatable umbrella showing my new design;

FIG. 2 is a side elevational view thereof;

FIG. 3 is a sectional side elevational view thereof as taken from line 3—3 of FIG. 1;

FIG. 4 is a side elevational view of another embodiment of my new design wherein a scalloped edge has been added thereto;

FIG. 5 is a sectional side elevational view thereof as taken from line 5—5 of FIG. 4.

I claim:

The ornamental design for an inflatable umbrella, as shown and described.
